CONTINUOUS FURNACE

William A. Morton, Mount Lebanon, and Howard F. Spencer, Pittsburgh, Pa., assignors to Amco, Incorporated, Pittsburgh, Pa., a corporation of Pennsylvania

Application July 10, 1934, Serial No. 734,466

13 Claims. (CL 263—8)

This invention relates to method of and apparatus for continuous and uniform heating of slabs, billets, blooms or the like, and it is among the objects thereof to provide a furnace design which embodies an improved firing and heat control system.

In the art of heating by continuous processes as heretofore practiced, it has been customary to fire the furnace at numerous points and in most instances at spaced longitudinal intervals, the furnace being divided for that purpose into a so-called heating and soaking chamber, thus establishing multiple heat zones of different temperatures. Such division of furnace heating chambers was accomplished by the employment of a roof structure having a drop or partition member that provided for a relatively long heating chamber and short soaking chamber, each of which was individually fired by regulable burners.

In accordance with the present invention, a furnace construction embodying a single or unit heating chamber is utilized and the application of the heating medium to the slabs or billets to bring them up to the necessary working or rolling temperature is accomplished in a novel manner to obtain the desirable input of heat without exposing any portion of the billets to excessive oxidizing or scaling temperatures, and by means of which maximum heating capacity is obtained.

Another object of the invention is the provision of means for preventing the infiltration of air at the discharge end of the furnace thereby, in effect, producing a reducing atmosphere at the point of maximum temperature to prevent scaling.

Still a further object of the invention is the provision of means for utilizing different fuels in conjunction with recuperator structures which are adapted to develop and maintain a high preheat of the air directed to the combustion zone.

Still another object of the invention is the provision of means for recirculating a part of the preheated air through the recuperator structure where gases of low B. t. u. value are utilized as fuel thereby substantially reducing the temperature differential between preheated air and waste gases in the walls of the recuperator tile.

Still a further object of the invention is the provision of means for heating light billets or the like which controls the temperature at the charging and discharging ends of the furnace chamber by directing the heat flame or products of combustion from a single firing source whereby great flexibility of heat control is provided.

These and other objects of the invention will become more apparent from a consideration of

the accompanying drawings constituting a part hereof in which like reference characters designate like parts and in which:

Fig. 1 is a vertical cross-sectional view longitudinally of a continuous heat furnace embodying the principles of this invention;

Fig. 2 a horizontal section taken along the line 2—2, Fig. 1;

Fig. 3 a vertical section transversely of the furnace taken along the line 3—3, Fig. 1; and

Fig. 4 a horizontal cross-sectional view taken along the line 4—4, Fig. 1.

With reference to the several figures of the drawings, the structure therein illustrated comprises a heating chamber generally designated by 15 the reference numeral 1 having a constricted charging end 2 and discharge passage 3; material such as billets or slabs 4 being supported on skid rails or water cooled pipes 5 and moved through the furnace by means of a pusher mechanism 6, 20 when the gate 7 is opened. As the billets advance toward the discharge end of the furnace, they travel from the rails 5 onto a solid uniformly heated hearth portion 8. The hearth 8 is provided with a sloping end 9 which, with a tapered 25 roof portion 10 of the heating chamber, forms the discharge passage 3 that is controlled by a gate 11, the billets being received on a feed-roll table 12 by which they are conveyed to the rolling mill. The door mechanisms are operated in timed relation with the pusher mechanism 6 so that the doors open only as a billet is being charged and discharged into and out of the furnace.

The tapered roof portion 10 at the discharge end of the furnace extends to a roof 13 which 35 is a flat arch as shown in Fig. 3 and gradually slopes downwardly towards the charging end 2 of the chamber. A burner port 14 is provided adjacent the apex of the sloping roof portions and burners 14a beneath the billets for the bottom 40 heating of heavy stock, there being as many burners or firing ports provided transversely of the hearth as is necessary to supply a heat flame of the width of the furnace. The sloping hearth portion 9 adjacent the discharge end of the furnace is provided with an exhaust passage 15, and exhaust passages 16 and 17 are provided beneath the billet supporting rails 5, passages 15, 16 and 17 communicating with recuperator structures 18 and 19 that are separated by a partition wall 20. 50 Dampers 16a and 17a are provided for passages 15 and 16 to independently regulate the withdrawal of the products of combustion through these passages, and a damper 21 controls exhaustion of the gases from the furnace chamber di- 55

rectly to a stack passage 22 to provide additional means to maintain desirable heat condition within the recuperator structure.

The arrangement of the recuperator chambers 5 is more clearly shown in Figs. 2 to 4 inclusive of the drawings in which they are shown divided by the walls 20 and 23, and walls 24 and 25, the latter being provided with openings 26 through which preheated air is conducted to a longitudinal 10 passage 27 and thence to a transverse passage 28. The heat exchange tile 29 is built up in the recuperator chambers, the tile forming vertical waste gas passages and horizontal air passages, the air passages being connected at the bottom 15 with a manifold 30 having conduits 31 extending to the bottom of the recuperator tile, each conduit being provided with a damper or gate 32 to regulate the quantity of air entering the different portions of the recuperator structures. 20

Manifold 30 has a transverse main 33 which is connected to a blower 34, the blower being also provided with a conduit 35 leading to the transverse passage 28. The preheated air passes upwardly from passage 28 through conduit 36 to a 25 burner 37 extending into the firing port 14 on the roof of the furnace. Gas ducts or mains 38 and 39 communicate with the burner 37, the duct 38 being of the lesser diameter as it supplies a natural rich fuel gas while the duct 39 is considerably 30 larger to supply a greater volume of fuel gas such as producer gas that is of a lower B. t. u. value than the natural gas and consequently used in greater volume.

A blower 34 is provided with a gate valve 40 that regulates the volume of air conducted to the manifolds 30 on the sides of the recuperators and a gate valve 41 for regulating the amount of preheated air drawn from the transverse passage 28 for recirculating with the cold air drawn in 40 through the passage controlled by the gate valve 40 for the purpose to be hereinafter explained.

The waste gases withdrawn from the furnace 1 through the exhaust passage 15 pass into the recuperator chamber 18 thence downwardly 45 through the vertical tile passages 42 to a horizontal passage 43 leading to the exhaust stack passage 44. Passage 43 is controlled by a gate 45. Similarly, the products of combustion exhausted through the passages 16 and 17 may be drawn 50 directly to the stack passage 22 controlled by the gate 21, or by closing gate 21 the exhaust gases may be drawn through the vertical recuperator tile passages 42 to an exhaust passage 46 leading to a stack passage 47 that is controlled by a 55 gate 48.

One of the features of the invention is the location of the discharge passage 3 below the horizontal plane of the furnace hearth 8 and also below the opening of the exhaust passage 15. By 60 so locating the discharge passage beneath the hearth and exhaust passage, infiltration of air is prevented. Any air passing into the discharge passage when, for example, the gate 11 is open, will be drawn through exhaust passage 15 and 65 be prevented from contacting the heated billets supported on the hearth 8. By preventing infiltration of air, scale and oxidization are largely eliminated and the withdrawal of air through the exhaust passage 15 produces a reducing atmosphere 70 in the portion of the furnace immediately adjacent the discharge passage 3.

The method of firing the furnace and regulation of the application of heat to the billets together with the control of the furnace temperature through regulation of the exhaust, and the

intensity and volume of the preheated air is as follows: The gaseous fuel is supplied through the burners 37 and 37a and a heat flame is directed as indicated by the arrows so as to impinge upon the hearth 8 at substantially its termination with the billet supporting skid rails 5. When the burner is first ignited, the exhaust 15 is shut off either through manipulation of the damper 15a or by closing gate 45 so that all of the heat is drawn beneath the long sloping roof portion towards 10 the charging end of the furnace, damper 16a likewise being shut off or closed for the initial heating of the furnace. Roof 13 is inclined or sloped as shown in Fig. 1 to reduce the volume 15 of the products of combustion toward the charging end of the furnace to obtain uniform heating, by lowering the level of movement of the gases as they pass to the exhaust opening 17. As the furnace chamber is brought up to temperature, billets 4 are charged into the heating chamber by 20 the pusher mechanism 6, each successive stroke of the pusher advancing the billets along the rail 5 a distance corresponding to the width of the billet, and as they approach the firing ports they will be subjected to maximum heat. On account 25 of the water cooled rails 5 producing cold spots or dark spots on the bottom of the billet, the solid hearth portion 8 is provided to uniformly heat the billet before being pushed over the inclined slope 30 of the discharge passage 3.

Dampers 15a and 16a are subsequently opened and gates 48 and 45 are wholly or partially opened while gate 21 is wholly or partially closed. Instead of the products of combustion passing 35 longitudinally of the furnace to the exhaust 17 and thence to the stack, they will partially be drawn to the exhaust passage 15 and may be partially withdrawn at the mid-portion of the heating chamber through the passage 16 and partially withdrawn through the end passage 17 40 thence through the tile structures of recuperator chambers 18, 19 and 19a, and through their respective stack passages 43 and 46.

Blower 34 is placed in operation and the gate 40 is opened an amount to supply a desired quantity of air to the manifolds 30 from which it is conducted through the gate controlled conduits 31 to the air passages of the recuperators. The air, as it is preheated, rises in the tile structure and passes through openings 26 of the recuperator walls 25 into the collecting air passage 27, thence to the transverse air passage 28 upwardly through conduits 36 to the burner 37. It is to be noted that after the preheated air leaves the recuperator tile passages, heat losses by radiation are prevented and it is further heated in the horizontal collecting passage 27 which is adjacent the hottest portion of the waste gas tile passage of the recuperator and beneath the exhaust passages 15 and 16.

Provision is also made for recirculating a part of the preheated air when the leaner fuel gases such as producer gas is employed. That is to say, if air is supplied to the recuperators in quantities adequate to support combustion when 65 a rich natural gas is employed, a lesser quantity of air is necessary where gases such as producer gases of lower B. t. u. are fired in the furnace. At the same time, it is necessary to maintain sufficiently low temperatures of the recuperator tile to 70 prevent overheating and breakage of the tile and to accomplish this a part of the preheated air is recirculated by exhausting the excess portion used for rich fuel from the transverse passage 28 through the blower conduit 35, this being accom- 75

plished by opening the gate 41 and regulating the gate 40 so a lesser quantity of cold air is drawn into the blower. By thus recirculating the air, the temperature differential between the inner and outer walls of the bottom recuperator tiles is substantially reduced or eliminated and a high preheat of air is maintained at the burner port.

By the arrangement of exhausting the products of combustion at the rear and front portion of the heating chamber and firing at an intermediate point between the charging end and discharging end, high flame temperatures may be directed to the billets greatly in excess of the final rolling temperature of the billets without heating the billets beyond the desired rolling temperature, thereby accelerating the heating and increasing the capacity of the furnace. By proper regulation of the exhaust through passage 15, loss of heat is prevented once the billets have been brought up to suitable rolling temperatures.

By means of the intermediate exhaust passage 16, the waste gas temperatures may be controlled for any desired heating rate. Cold steel entering the furnace has a higher temperature differential with the waste gases than the steel in the area adjacent the exhaust passage 16 and by manipulation of the dampers, this heat differential may be reduced at the charging end and increased above the ordinary in the intermediate area so that more uniform heat absorption prevails along the hearth.

Accordingly, by means of the exhaust passage 16, temperature differential and the heat rate along the hearth is balanced or controlled to maintain a more nearly constant condition. When more heat is drawn down passage 16 as a result of increased tonnage, the temperature in the recuperator is increased, and increased air preheat temperatures follow. This automatically increases the flame temperature above the solid hearth portion and assists in maintaining the desired temperature differential by which the heat rate may be accelerated.

By dividing the heat exchangers into groups of chambers with separate damper control, more effective regulation of the heat in the furnace is attainable. Also by the employment of the unit heating chamber, the furnace is particularly adapted to the use of producer gas fuel which does not efficiently lend itself to a large number of burners of small fuel capacity.

From the foregoing description of the invention, it is evident that such a furnace structure is adapted to maintain uniform heat of billets, ingots, slabs or the like in an economical manner as its regular uniform external wall surface requires a minimum input of heat and is adapted to the utilization of the cheaper fuels. By recirculating part of the preheated air, the tile at the exhaust end of the recuperator passages is maintained at suitable temperatures and a high preheat is available for efficient and economical firing.

Although an embodiment of the invention has been herein illustrated and described, it will be evident that various modifications may be made in the details of construction and in the arrangement of parts without departing from the principles herein set forth. It is also apparent that the method of firing and heat control is applicable to continuous heating of articles other than billets, slabs or the like.

We claim:

1. A continuous heating furnace comprising an elongated heating chamber having an inclined

roof from the charging end towards the discharge end of the chamber and an inclined roof from the discharge end towards the charging end forming an apex remote from the charging end and near the discharge end of the chamber, a hearth disposed within the chamber below the end of the roof at the charging end and above the end of the roof at the discharge end, an exhaust passage adjacent the charging and discharge ends of said chamber extending beneath the hearth and means for withdrawing the products of combustion from the chamber in divided paths through the said exhaust passages.

2. A continuous heating furnace comprising an elongated heating chamber having charge and discharge openings at opposite ends, a hearth extending longitudinally of the chamber, exhaust passages in said hearth, recuperator tile structures beneath said hearth communicating with said exhaust passages and separated by partition walls dividing the recuperator structures in separately controllable sections, burner ports in said heating chamber, means for withdrawing the products of combustion through the exhaust passages direct to the stack, means for conducting the products of combustion through said recuperator sections, means for directing air through the recuperator structures in heat exchange relation with the waste gas passages, means for conducting the preheated air from the recuperator structures to the burner port, and means between the recuperator and the furnace for regulating the volume of air supplied to the furnace independent of that supplied to the recuperator sections.

3. A continuous heating furnace comprising an elongated heating chamber having an inclined roof extending from a maximum elevation at a portion of the chamber near the discharge end thereof to the charge and discharge openings of the chamber, a burner disposed through the roof adjacent the apex thereof disposed to direct a heat flame toward the hearth in the direction of the charging end of the furnace chamber, a plurality of recuperator structures beneath the hearth of the heating chamber, an exhaust passage adjacent the discharge end of the furnace with the mouth of the passage above the discharge opening of the chamber, said exhaust passage being in communication with said recuperator structures, an exhaust passage adjacent the charging end of the chamber in communication with the recuperator structures, means for withdrawing the products of combustion from the heating chamber through the several exhaust passages and their respective recuperator structures, means for supplying air to the recuperators and for withdrawing the preheated air through a passage leading to the burner ports, and means for independently regulating the quantity of cold and heated air supplied to different portions of the recuperator structures.

4. A continuous heating furnace comprising an elongated chamber having a flat arch roof sloping from a maximum elevation near the discharge end of the chamber towards a charge and discharge opening at opposite ends of the chamber, a recuperator structure beneath the hearth of said chamber, an exhaust passage adjacent the charging and discharge ends of the chamber extending beneath the hearth and communicating with the recuperator structure, exhaust means for withdrawing the products of combustion from the heating chamber through the exhaust passages in regulable amounts and

from the exhaust passages through the recuperator structures to a stack, means for supplying air to the bottom of the recuperator structures, and means for collecting the preheated air from the recuperator structures near the top thereof and conducting it to the burner ports of the heating chamber.

5. A continuous heating furnace comprising an elongated heating chamber having a charging and discharge opening at opposite ends, exhaust 10 passages extending through the hearth adjacent the charge and discharge openings, an exhaust passage extending through the hearth intermediate said first named passages, a recuperator structure beneath the hearth of the heating chamber in communication with the exhaust passages of the chamber, partition walls dividing said recuperator structures into independently controllable units for the respective exhaust 15 passages, means for by-passing the products of combustion around said recuperator structures to a stack and means for moving the products of combustion through the exhaust passages and controlling the movement at will in the respective 20 recuperator structures to the stack, means for supplying air to the recuperator structures, means for collecting the preheated air from all of the recuperator structures and conducting it in heat exchange relation with the exhaust 25 passages of the chamber to the burner ports, and means for regulating the quantity of air supplied to the several recuperator sections.

6. A continuous heating furnace comprising an elongated chamber having charge and discharge 30 openings at opposite ends and having exhaust passages extending through the hearth, the discharge passage of the chamber being below the level of the hearth, burner ports disposed in the roof of the chamber for directing a heating flame 35 towards the hearth and in the direction of the charging end of the furnace chamber, a recuperator structure beneath the hearth, means for withdrawing the products of combustion through the exhaust passages into the recuperator structure, and thence to a stack, means for supplying 40 air to the recuperator structures at the bottom thereof and withdrawing the preheated air through a passage common to all the recuperators and conducting the preheated air to the burner ports, and means for withdrawing a portion 45 of the preheated air and recirculating the same through the air preheat passages of the recuperator structures.

7. A continuous heating furnace comprising an elongated heating chamber having parallel skids 50 for a portion of its length to support the articles to be heated in spaced relation with the hearth, said skid members terminating in a solid hearth portion near the discharge end of the furnace chamber whereby the articles to be heated are initially 55 conveyed along the skid members and subsequently on the solid hearth portion, burners in said chamber below and above said skid members, the burners being located to direct a heating flame on the work at substantially the juncture of the skid members and solid hearth portion, and means for withdrawing the products of combustion in desired volumes from the top 60 burners to effect a division thereof at substantially the juncture of the skid members and the said solid hearth portion.

8. A continuous heating furnace comprising an elongated heating chamber having its roof wall inclining from an apex adjacent the discharge 65 end of the furnace towards the respective ends of

the furnace, a pair of work-supporting skids extending longitudinally of the furnace chamber for supporting the articles to be heated out of contact with the furnace hearth for a major portion of their travel through the furnace and a solid 5 work-supporting hearth portion forming an extension with said skid members beneath the apex of the furnace roof and sloping sharply downward to the discharge opening of the furnace, heating means comprising a gaseous burner extending through the roof of the furnace above the work-supporting hearth that constitutes a continuation of the skid members, burners beneath said skid members and means beneath the hearth and skid members for withdrawing the 10 products of combustion from the gaseous burner in divided paths towards the respective ends of the furnace chamber.

9. A continuous heating furnace having a work-supporting hearth substantially horizontal 20 throughout one end of said hearth declining sharply to constitute a discharge chute for the articles passing through the furnace, a combustion chamber provided above said hearth and waste gas passages beneath the hearth at the 25 respective ends thereof, the waste gas passage at the discharge end being beneath the inclined portion of the hearth and above the discharge opening of the furnace chamber.

10. A continuous heating furnace having a 30 work-supporting hearth substantially horizontal throughout one end of said hearth declining sharply to constitute a discharge chute for the articles passing through the furnace, a combustion chamber provided above said hearth and waste gas passages beneath the hearth at the 35 respective ends thereof, the waste gas passage at the discharge end being beneath the inclined portion of the hearth and above the discharge opening of the furnace chamber, and regulable means 40 controlling the exhaustion of the products of combustion from the heating chamber through the waste gas passages.

11. A continuous heating furnace comprising a heating chamber and a hearth with a charging 45 opening at one end and a discharge opening at the opposite end, a product-supporting hearth extending longitudinally of said chamber and having its upper level coextensive with the charging opening and above the discharge opening, 50 burners disposed intermediate the charge and discharge ends of said chambers, and exhaust means for withdrawing products of combustion in desired quantities simultaneously at different 55 points across the hearth of the furnace adjacent the discharge end.

12. A continuous heating furnace comprising a heating chamber and a hearth with a charging opening at one end and a discharge opening at the opposite end, a product supporting hearth 60 extending longitudinally of said chamber and having its upper level coextensive with the charging opening and above the discharge opening, burners disposed intermediate the charge and discharge ends of said chamber, and spaced 65 damper controlled exhaust means adjacent the discharge end of the furnace and connected thereto substantially beneath the hearth for withdrawing products of combustion from the furnace.

13. A continuous heating furnace comprising an elongated heating chamber having an inclined roof from the charging end towards the discharge end of the chamber and an inclined roof from the discharge end towards the charging end forming 70

an apex remote from the charging end and near the discharge end of the chamber, a hearth disposed within the chamber below the end of the roof at the charging end and above the end of the roof at the discharge end, an exhaust passage adjacent the charging and discharge ends of said chamber and an exhaust passage intermediate

said end exhaust passages, said exhaust passages extending beneath the hearth, and means for withdrawing the products of combustion from the chamber selectively in divided paths through the said exhaust passages.

WILLIAM A. MORTON.
